UNITED STATES PATENT OFFICE.

JOSEPH FERGUSON, OF PHILADELPHIA, PENNSYLVANIA, ASSIGNOR TO
STEAD & MILLER, OF SAME PLACE.

DESIGN FOR A CURTAIN FABRIC.

SPECIFICATION forming part of Design No. 15,926, dated March 10, 1885.

Application filed January 10, 1885. Term of patent 3½ years.

To all whom it may concern:

Be it known that I, JOSEPH FERGUSON, a citizen of the United States, residing at Philadelphia, in the county of Philadelphia and State of Pennsylvania, have invented and produced a new and original Design for a Curtain Fabric: and I do hereby declare that the photographic print accompanying this specification conveys to any one skilled in the art a clear understanding of the same, and is sufficient to enable such person to use my invention.

The leading feature of my design consists in the representation at E of a water-pond, water-lilies, leaves, branches, and flowers of other water-plants, and ornamental cross-border

or guard F, which whole makes the ornamental design of a dado for a curtain fabric, as shown in the photographic print accompanying this specification.

I claim as my invention and desire to secure by Letters Patent—

The representation consisting of the water-pond, water-lilies, leaves, branches, and flowers of other water-plants, and ornamental cross-border or guard F, which whole makes the ornamental design of a dado for a curtain fabric, as shown.

JOSEPH FERGUSON.
